DESIGN FOR AN ELECTRICIAN'S TEST SET

Alexander J. Heidt, Woodhaven, N. Y.

Application June 23, 1938, Serial No. 78,001

Term of patent 14 years

To all whom it may concern:

Be it known that I, Alexander J. Heidt, a citizen of the United States, residing at Woodhaven, in the county of Queens, Long Island, and State of New York, have invented a new, original, and ornamental Design for an Electrician's Test Set, of which the following is a specification, reference being had to the accompanying drawing, forming part thereof, in which

Fig. 1 is a view in side elevation of an elec-trician's test set incorporating my new design, with lamp bulbs and their guards shown in broken lines.

Fig. 2 is an end view of the device, on a smaller scale than Fig. 1, and omitting the lamp bulbs and their guards.

I claim:

The ornamental design for an electrician's test set, as shown.

ALEXANDER J. HEIDT.
